[57] CLAIM

The ornamental design for a stackable tray for cans, as shown and described.

DESCRIPTION

FIG. 1 is a top perspective view of a stackable tray for cans showing our new design;
FIG. 2 is a bottom perspective view thereof;
FIG. 3 is a top plan view thereof;
FIG. 4 is a bottom plan view thereof;
FIG. 5 is a right side elevation thereof, the left side elevation being a mirror image;
FIG. 6 is a front elevation thereof, the rear elevation being a mirror image thereof;
FIG. 7 is a top perspective view of a modified form of FIG. 1;
FIG. 8 is a bottom perspective view of FIG. 7;
FIG. 9 is a top plan view of FIG. 7;
FIG. 10 is a bottom plan view of FIG. 7;
FIG. 11 is a right side elevation of FIG. 7, the left side elevation being a mirror image; and
FIG. 12 is a front elevation of FIG. 7, the rear elevation being a mirror image.
